INSECT LAMP TRAP

John C. Gardner, Horicon, Wis., assignor to Gardner Manufacturing Co., a corporation of Wisconsin

Filed June 2, 1961, Ser. No. 65,430

Term of patent 14 years

(Cl. D31—3)

FIG. 1 is a side elevational view of an insect lamp trap, showing my new design.

FIG. 2 is a rear elevational view thereof rotated 90° to the right of FIG. 1.

FIG. 3 is a bottom plan view thereof.

The side not shown is substantially like the side shown.

I claim:

The ornamental design for an insect lamp trap, as shown and described.
